J. E. ROBINSON

BOTTLE CARRYING DEVICE

Filed March 15, 1926

FIG. 1.

FIG. 2.

INVENTOR
Joseph E. Robinson
BY *U. G. Charles*
ATTORNEY.

UNITED STATES PATENT OFFICE.

JOSEPH E. ROBINSON, OF TOPEKA, KANSAS.

BOTTLE-CARRYING DEVICE.

Application filed March 15, 1926. Serial No. 94,835.

My invention relates to a bottle carrying device.

The object of my invention is to provide a holder for milk bottles or other containers of various sizes which is easily applied or removed.

A further object of my invention is to provide an inexpensive though sturdy device which will facilitate the handling of glass bottles either singly or in multiple.

These and other objects will hereinafter be more fully explained.

Referring to the drawings:

Fig. 1 is a side view of the holder in position on the neck of a glass bottle of the type which is generally used as a milk container.

Fig. 2 is an elevation of the holder when disengaged.

The mechanism herein disclosed consists of a wire bail 1 having a curvature centrally disposed, the radius of which is approximately the same as that of the neck of a milk bottle. A transverse curve is then provided for each of the bail members, whereby the straight portions tangent therewith are approximately in alignment with the bottle longitudinally. The upper end portions of the bail members have reversed curvatures as at C to the last said curvatures, and a right angle bend of each bail member extending toward each other and in alignment to engage axially in an apertured handle 2, the ends of the right angle portions being in close proximity as shown at A. The bail thus formed positions the handle to one side of the axial alignment of the bottle, by which means the yoke 3 hereinafter described will co-act with the bail, gripping firmly to the neck of the bottle 4 when being raised.

A yoke gripping means 3 is attached to the bail 1 as indicated at B, and slidably engaging thereon. Both of the members 1 and 3 are shaped to conform to the periphery of the bottle neck when in carrying position, and when disengaged will permit easy passage of the rim of the bottle 4.

When the holder is in position on the neck of the bottle and a lifting or vertical force in an upward direction is applied to the handle 2 the offset at C of member 1 causes a pressure at the points D and E by means of the curvature of the bail at D', resulting in a grip on the bottle neck below the rim which increases in proportion to the weight of the bottle and its contents.

The holder herein described is preferably made of iron wire but I do not confine the holder to any particular type of material.

The mechanism herein disclosed may be applied as a carrying means for jars having tops of greater diameter and a rim thereon under which the yoke will engage.

The mechanism will also function as a clutch gripping to a form without relying on a rim or enlargement to prevent passage from the end thereof. Therefore modifications will be employed to meet the various conditions and objects to be carried; and other modifications may be employed as lie within the scope of the appended claim.

Having thus described my invention, what I claim as new and desire to secure by Letters Patent is:—

In a bottle carrying device, in combination with the neck of a bottle, a bail of the kind described having a centrally disposed curve and transversely positioned curves to the first said curve for each of the bail members, and a reverse curve to the second said curve to engage with a handle member, whereby the handle is eccentrically positioned to the vertical axis of the neck of a bottle, a yoke member having both ends looped to form eyes to slidably engage on the bail so that by raising the bottle the centrally disposed curve of the bail and the yoke will grip on the neck thereof by reason of the eccentrically positioned handle to the axis of said bottle.

JOSEPH E. ROBINSON.
